CLAIM

We claim the ornamental design for a cooking tray, as shown and described.

DESCRIPTION

FIG. 1 is an isometric view, from the top left, of a cooking tray, showing our new design;

FIG. 2 is an isometric view, from the bottom right, thereof;

FIG. 3 is a left-side elevation view, thereof;

FIG. 4 is a right-side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is a cross-sectional elevation view along the 9-9 cross section indicated in FIG. 5.

The broken lines in the drawings depict portions of the cooking tray that form no part of the claimed design.

1 Claim, 7 Drawing Sheets
